UNITED STATES PATENT OFFICE.

AMOS C. BARTLETT, OF HARTFORD, CONNECTICUT, ASSIGNOR TO B. F. STURTEVANT COMPANY, OF BOSTON, MASSACHUSETTS, A CORPORATION OF MASSACHUSETTS.

REVERSIBLE-WINDOW-BOARD SET.

1,030,962.

Specification of Letters Patent.

Patented July 2, 1912.

Application filed July 6, 1910. Serial No. 570,546.

To all whom it may concern:

Be it known that I, AMOS C. BARTLETT, a citizen of the United States, residing at Hartford, in the county of Hartford and 5 State of Connecticut, have invented certain new and useful Improvements in Reversible-Window-Board Sets; and I do hereby declare the following to be a full, clear, and exact description of the invention, such as 10 will enable others skilled in the art to which it appertains to make and use the same.

The invention relates to ventilating apparatus, and more particularly to an apparatus which is adapted to be arranged in a 15 window casing.

The object of the invention is to provide an apparatus of this character having a novel and improved construction and arrangement of parts which enables it to be 20 readily and conveniently adjusted to either blow fresh air into a room, or to exhaust the foul air from the room.

To these ends the invention consists in the features of construction and combinations 25 of parts hereinafter described and referred to in the claims.

The various features of the invention will be readily understood from an inspection of the accompanying drawings and the following detailed description of the apparatus 30 shown therein.

In the drawings, Figure 1 is a plan view partly in section of a ventilating apparatus embodying the features of the invention in 35 their preferred forms, and Fig. 2 is a sectional elevation on line 2-2, Fig. 1, looking in the direction of the arrows.

As shown in the drawings, the various parts of the apparatus are secured upon a 40 partition 1 in the form of a window board which may be readily secured to the window casing at the top or bottom, as may be most convenient. As shown, the devices for securing the window board in place consist 45 of clips 2 secured at the opposite ends of the board and adapted to embrace the flanges 3 of brackets 4 which may be screwed to the window casing. The board may be secured directly inside of the window sash, 50 so that the outside of the board is exposed when the sash is partially raised or lowered, as the case may be.

The board or partition 1 is provided with an inlet opening 5 and with an outlet opening 6. The outlet opening 6 communicates

with an outlet piece 7 secured to the inner face of the board, which is preferably in the form of a short cylinder or pipe. The outlet opening may be opened or closed by a valve plate 8 supported in a guideway 60 formed in the flange of the outlet piece. The inlet opening 5 communicates with the outer end of an inlet box or casing 9 which is secured to the inner face of the board. The inner end of the inlet box is semi-cylindrical in shape, and is cut away to form a port 10.

A centrifugal fan wheel 11 is mounted upon the board 1, and is provided with a snail casing 12 having a lateral inlet eye 13 70 and a tangential discharge 14. The fan wheel is secured to the shaft 14' of an electric motor 15 which is mounted upon the board 1. The rear side of the fan casing is secured to a cap 16 which forms the front 75 end of the motor casing. The cap 16 is provided with a flange 17 fitting within a flange 18 on the motor casing, and held frictionally against rotation by screws 19 which are provided with conical ends entering a 80 V-shaped groove in the flange 17. This manner of supporting the fan casing enables the casing to be turned about the axis of the fan, and the parts are so arranged that the discharge end 14 of the casing may be brought into engagement with the outlet piece 7, as shown in dotted lines in Fig. 2, or may be turned down into the full line position of Fig. 2. A cylinder 20 is secured to the eye 13 of the fan casing, and is arranged to fit within the semi-cylindrical end 85 of the inlet box 9. One side of this cylinder is cut away at 21 to form a port which is either open to the inlet box or open to the room within which the apparatus is located, according to the adjustment of the fan casing. The closed side 22 of the cylinder forms a valve which either closes the port 20 90 at the inner end of the inlet box, or cuts off communication between the eye of the fan and the inlet box, according to the adjustment of the fan casing.

When it is desired to draw air from the outside and blow it into the room, the fan casing is adjusted into the position indicated in Fig. 1, and in full lines in Fig. 2, and the valve plate 8 is placed in position to close the outlet opening 6 in the window board. With the parts thus adjusted, the port 20 in the inlet box is closed, and the 100 105 110

eye of the fan is in communication with the inlet opening 5 through the inlet box and port 21. The air will now be drawn in through the inlet opening 5, and be delivered by the fan through the discharge 14 into the room. When it is desired to exhaust air from the room, the fan casing will be swung up into the dotted line position indicated in Fig. 2, and the valve plate 8 will be removed. The discharge 14 will now be in communication with the discharge opening 6. The adjustment of the casing into the dotted line position turns the cylinder 20 through a half revolution, thus cutting off communication between the eye of the fan and the inlet opening 5, and opening communication between the eye of the fan and the room within which the apparatus is located. When the fan is rotated, air will now be drawn from the room through the eye of the fan casing and will be delivered from the discharge 14 through the outlet opening 6.

While it is preferred to employ the construction and arrangement of parts shown and described, and to provide for reversing the connections between the eye and discharge of the fan casing so that air may be blown in or exhausted out of the room by adjustment of the fan casing, it will be understood that this construction and arrangement is not essential to the broader features of the invention, and that the reversal of the flow of air through the partition may be otherwise secured without departing therefrom. While the invention has been illustrated and described in connection with its application to a window ventilating set, it will be understood that the invention is not confined in its application to such use, but may be utilized in other relations where it is desirable to induce a current of air through a partition and to reverse the direction of flow at will.

Having explained the nature and object of the invention, and specifically described one form of apparatus in which it may be embodied, what I claim is:

1. A ventilating apparatus, having, in combination, a partition provided with inlet and outlet openings, a fan, a fan casing provided with an inlet eye and a discharge, and means for either opening communication between the inlet opening and eye and closing the outlet opening, or opening communication between the discharge and outlet opening and closing the inlet opening, substantially as described.

2. A ventilating apparatus, having, in combination, a partition provided with inlet and outlet openings, a fan, a fan casing provided with an inlet eye and a discharge, means for bringing the discharge of the casing into or out of communication with the outlet opening, and means for bringing

the eye of the fan into or out of communication with the inlet opening, substantially as described.

3. A ventilating apparatus, having, in combination, a partition provided with inlet and outlet openings, a fan, a fan casing provided with an inlet eye and a discharge, means for bringing the discharge of the casing into or out of communication with the outlet opening, means for bringing the eye of the fan into or out of communication with the inlet opening, and means for closing the opening in the partition which is out of communication with the fan casing, substantially as described.

4. A ventilating apparatus, having, in combination, a partition provided with inlet and outlet openings, a fan, a fan casing provided with an inlet eye and a discharge, means for supporting the casing for movement to bring the discharge either into or out of communication with the outlet opening, and means for opening or cutting off communication between the eye and the inlet opening, substantially as described.

5. A ventilating apparatus, having, in combination, a partition provided with inlet and outlet openings, a fan, a fan casing provided with an inlet eye and a discharge, means for supporting the casing for movement to bring the discharge into or out of communication with the outlet opening, and a valve connected with the casing for opening and closing communication between the inlet opening and eye, substantially as described.

6. A ventilating apparatus, having, in combination, a window board provided with inlet and outlet openings, a motor mounted thereon, a fan on the motor shaft, a casing provided with a lateral eye and tangential discharge and mounted for movement about the axis of the fan to bring the discharge into or out of register with the outlet opening, an inlet box, and a valve cylinder in the inner end of the box connected to communicate with the eye of the fan casing, substantially as described.

7. A ventilating apparatus, having, in combination, a window board provided with inlet and outlet openings, a centrifugal fan mounted on the board, a casing for the fan provided with a lateral eye and tangential discharge and mounted for movement about the axis of the fan to bring the discharge into or out of register with the outlet opening, an inlet box provided with an opening in its inner end, and a cylinder connected with the eye and having one side cut away and arranged to open into the inlet box when the discharge of the casing is out of register with the outlet opening and to register with the opening in the inner end of the box when the discharge is in register with the outlet opening, substantially as described.

8. A ventilating apparatus, having, in combination, a partition, a centrifugal fan, a fan casing provided with a lateral inlet eye and a tangential discharge, and devices adjustable to either put the eye into communication with the space outside of the partition and the discharge into communication with the space inside the partition, or put the eye into communication with the

space inside the partition and the discharge 10 into communication with the space outside the partition whereby the fan may induce a current of air through the partition in either direction, substantially as described.
